US0D1005634S

(12) **United States Design Patent** (10) **Patent No.:** **US D1,005,634 S**
(45) **Date of Patent:** **** Nov. 21, 2023**

(54) **COATING MATERIAL CONTAINER**(71) Applicant: **SWIMC LLC**, Cleveland, OH (US)(72) Inventors: **Michael C. Lambertson, Jr.**, Aurora, OH (US); **Joshua R. Robertson**, North Ridgeville, OH (US)(73) Assignee: **SWIMC LLC**, Cleveland, OH (US)(***) Term: **15 Years**(21) Appl. No.: **29/883,467**(22) Filed: **Jan. 30, 2023****Related U.S. Application Data**

(63) Continuation of application No. 29/764,268, filed on Dec. 29, 2020, now Pat. No. Des. 980,571, which is a continuation of application No. 29/682,054, filed on Mar. 1, 2019, now Pat. No. Des. 908,999.

The ornamental design for a coating material container, as shown and described.

DESCRIPTION

FIG. 1 is a perspective view of a coating material container showing our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.
